CLAIM

The ornamental design for a bottle, as shown and described.

DESCRIPTION

FIG. 1 is a rear right side perspective view showing the new design for a bottle;

FIG. 2 is a rear left side perspective view thereof;

FIG. 3 is a front right side perspective view, taken from beneath the bottle;

FIG. 4 is a front left side perspective view, taken from beneath the bottle;

FIG. 5 is a right side view thereof;

FIG. 6 is a left side view thereof;

FIG. 7 is a rear view thereof;

FIG. 8 is a front view thereof;

FIG. 9 is a bottom plan view thereof; and,

FIG. 10 is a top plan view thereof.

The broken lines show portions of the bottle that form no part of the claimed design.
